TYPEWRITING MACHINE

Louis C. Antrim, New York, N. Y.

Application December 7, 1931, Serial No. 579,390

56 Claims. (Cl. 197—126)

This invention relates to typewriting machines, and more particularly, to means for facilitating the making of multiple copies.

As in my prior application, Serial No. 410,477, filed November 29, 1929, on which this invention is an improvement, the transfer medium of the present invention is in the form of a disk entering between the superposed strips or sheets carried by the platen of the typewriter and 10 adapted to roll through the superposed strips as the typewriter carriage is moved in letter-feeding direction.

A feature of the present invention is the provision of means mounted at one side of the typewriter for holding the transfer disks in operative position at the printing point, thus leaving one side of the machine free from any encumbrances.

In the form of the invention illustrated, which is that at present preferred, the means for holding the carbon disks comprises a plurality of arms pivotally mounted on the supporting means and movable into operative position from an out-of-the-way position up away from the platen, the mounting of the arms and their supporting means being an important feature of this invention.

In my prior application, the mounting for the transfer disks was so arranged that the circumferential margin of the disk could be moved vertically with relation to the line of writing, so that the operator by manual adjustment could utilize the greater portion of the annular margin of the transfer disk. However, it was found that with this arrangement, the fact that the 35 carbon was becoming worn would not be noticed by the operator until after the impressions had become very weak.

According to the present invention, and this is an extremely important and advantageous feature thereof, the transfer strip is moved vertically with relation to the line of writing as well as being rotated during the travel of the typewriter carriage, thereby distributing the impressions taken from the transfer disk over a 45 substantially wide annular margin of the disk.

Again, with my prior device, since it rotated during both the leather-feeding and return movements of the typewriter carriage, the relation of each part of the annular margin of the disk to a part of the line of writing was substantially constant. Hence, those portions of the transfer disk related to the portion of the line 50 of writing receiving the greatest number of impressions would become worn and exhausted of

transfer material before other portions of the annular margin of the disk.

This is obviated by the present invention by holding the disk raising and lowering device against rotation during the return movement 60 of the carriage and causing the first impression of the next line of writing to be in an entirely different place from the first impression of the previous line of writing.

A further feature of this invention is the provision of means for pressing the superposed strips and transfer disks together above the line of writing to thereby avoid the presence of air pockets between the strips and disks at the line of writing and thereby cause the impressions to 70 be sharp and clear.

A still further feature of this invention is the provision of improved means for attaching and mounting the carbon arm supporting means on a typewriter frame, the clamping means being 75 so arranged as to fit the frame of any typewriter on the market.

Other features and advantages will herein-after appear.

In the accompanying drawings—

80

Fig. 1 is a front elevation of a typewriter showing my invention applied thereto—the manner of removing a written form being illustrated.

Fig. 2 is a diagrammatic view showing the platen and the transfer disk of this invention, 85 and indicating in dot-and-dash lines the positions which the disk takes vertically at various points in the travel of the typewriter carriage.

Fig. 3 is a side elevation of the device shown in Fig. 1.

15 Fig. 18 is a detail view showing the means for attaching the supporting arm to a typewriter frame and taken on the line 18—18 of Fig. 3.

Fig. 19 is a front elevation of the paper guide and its supporting arm in the same positions as the parts shown in Fig. 1, but on an enlarged 20 scale.

The typewriting machine shown in the accompanying drawings is of a conventional type having a cylindrical platen 20 rotatably mounted in a carriage 21 which itself is mounted for longitudinal movements in a frame 22 under the control of letter-feed mechanism not shown. In front of the platen there is a ribbon 23 against which type bars 24 are adapted to strike and cause impressions to be made on the uppermost 25 of the worksheets or strips 25 when the keys 26 are operated; the keys 26 in their operation also causing the platen 20 and carriage 21 to move step-by-step toward the left. After a line has been written, the carriage 21 may be returned by means of a lever 27, operation of which, through line-spacing mechanism 28, causes the platen to be rotated to bring a fresh portion (i. e. the next line) of the worksheets or strips to the line of writing. The work 25, which may 30 be in either sheet or strip form, is led to the platen over the usual paper table 29 and is held against the platen to be advanced by the rotation of the latter by feed rollers 30.

Ordinarily, in order to cause the impressions 45 of the type bars 24 to print on the under worksheets or strips, which, for convenience, will be indicated by the numerals 25a and 25b when referred to specifically, sheets of carbon paper are interposed between the several worksheets or 50 worksheet strips, but these sheets require considerable handling, causing such inconvenience that many efforts have been made to obviate the need for them.

As in my prior application, this is done by the 55 use of disks or wheels 31, which may be made of paper or other material impregnated with ink or coated with carbon or other transfer material. The entire disk 31 may be coated or impregnated, or, if desired, only an annular marginal portion 60 thereof, the inner boundary of which is indicated by dotted lines in Fig. 2, may be so treated. In either event, as in my copending application above referred to, the carbon disks are supported at the printing point of the type bars 24 and have 65 their marginal edges projecting between the worksheets 25, 25a and 25b, or any of the latter, so that when the type bar 24 prints upon the top sheet 25 through the ribbon 23, an impression will also be made on the sheets 25a and 25b by the 70 transfer disks 31.

As disclosed in my prior application above referred to, each transfer disk is mounted in a bail which is fulcrumed at opposite sides of the typewriter and which may be swung up out of the way 75 when desired. According to the present inven-

tion, however, and so as to permit one side of the typewriter to be free and unencumbered by the attachment of the present invention, the carbon disks 31 are each mounted near the loose end of a carbon arm 32, see Fig. 6. The carbon arms 32 near their other ends are mounted on a shaft 33 carried in a frame 34 and are spaced from each other by spacing washers 35. Each carbon arm 32 has an extension 36 beyond the shaft 33 normally urged downwardly by a spring 37 and therefore has a tendency to raise the disk supporting end of the arm 32 and carry the disk 31 out of the line of writing, as indicated by the most rearward carbon arm and disk in Fig. 5. When, however, the carbon arm and disk is intentionally depressed so as to enter the line of writing, the extension 36 of that arm is engaged by a latch 38 and held in that position. The latches 38 are pivotally mounted on a rod 39 and are urged toward operative position by springs 40. The upper ends of the latches 38 are provided with numbered fingerpieces 41 which may be canted, as has occurred to lever No. 4 in Fig. 12, to release the extension 36 and allow the carbon arm 32 and disk 31 carried thereby to rise and remove the disk 100 from the line of writing—this being a non-print position of the carbon disk.

So far as its carbon arm carrying function is concerned, the carbon arm frame 34 could terminate adjacent the shaft 33. However, to form 105 a handle by means of which the frame may be swung in manners and for purposes hereinafter referred to, to form a protective casing for the carbon arms in use, to carry means for controlling the position of the carbon arms relative 110 to the writing line, and, for holding the worksheets together at the printing point, the frame 34 is provided with two long arms 42 and 43 extending to the printing point of the machine. The carbon arm frame is also pivotally mounted 115 on the shaft 33 which is carried in an arm 44 having a square or other noncircular extension 45, see Fig. 13, wherein this is accomplished by having the shaft 33 threaded in a shaft 44 and provided with a shoulder 46 engaging the arm 43 of 120 the frame fitting in a supporting bracket indicated as a whole by the reference numeral 47.

Thus it will be seen that the carbon arm frame 34 with the carbon arms 32 and disks 31 may be swung as a unit upwardly out of the line of writing 125 and completely out of the way of the typewriting machine and, of course, it may be swung from this out-of-the-way position down to position for writing. In its lower or operative position, the carbon arm frame is held at a predetermined 130 height by means which, according to the present invention, engages the platen 20 of the typewriter. When the disks are in operative position, the letter-feeding movements of the platen and the paper carried thereby will cause the disks 31 to 135 each roll down into the line of writing and remain interposed between two adjacent worksheets 25. On the return of the carriage, after the paper has been line-spaced, the disks can again roll, but this time in the reverse direction, through the 140 line of writing and are brought at the end of the carriage return operation to position to receive the next impression through the type bars 24.

In my prior application above referred to, the 145 transfer disks roll back and forth in the line of writing at a predetermined depth with relation thereto. After the transfer material of the portion of the disk utilized, while the disk was at this definite depth, became consumed and made weak 150

impressions, the operator would make an adjustment to increase or decrease the depth of the disks relative to the line of writing so as to bring a fresh annular zone on the carbon disk into use.

5 Moreover, with this arrangement, there being nothing to avoid it, each time the carriage was returned the same point on the disk would be located at the printing point the disk rolling as much in one direction as another. Accordingly, 10 if greatest efficiency was to be obtained the disk would have to have a circumference substantially equal to the length of the line of writing—otherwise there would be an unused portion on each disk when the other portions became consumed. 15 This is avoided by the present invention by causing the carbon disks to oscillate vertically as well as rotate during the letter-space movements of the carriage and by preventing oscillation but permitting rotation if desired during the return 20 movement of the carriage.

This is accomplished by providing the arm 43 of the carbon arm frame with an eccentric roller 48 carried on a boss 49 on the arm 67. The arm 67 is adjusted, in a manner hereinafter referred 25 to, so that the roller 48 rides on the top surface of the cylindrical platen 20 and, as the platen travels with relation to the carbon arms and the printing point of the machine, the roller 38 causes the carbon arm frame 34 to be raised and lowered, the frame 34 pivoting during this motion on the shaft 33.

During the return travel of the carriage, however, rotation of the roller 48 is prevented by a ratchet wheel 50 carried by it, see Figs. 4 and 5, 35 which is engaged by a dog 51. Hence, as indicated diagrammatically in Fig. 2, the center of the disk 31 follows an irregular path, indicated by dot-and-dash lines provided with arrow heads, during the rotation of the roller 48 while the carriage is feeding toward the left, and in a straight line from wherever it happened to be stopped by the dog 51 when the carriage is returned toward the right.

Thus the relative positions between the platen 45 and the disk 31 become changed at the beginning of each new line and in this way the entire usable surface of the disk is employed.

It should be understood that in the matter of regulating the positions of the transfer disks relative to the line of writing by means engaging 50 the platen, in the broader aspects of this invention it is immaterial whether an eccentric wheel, a plain concentric wheel, or a shoe, be used for this purpose. The eccentric wheel distributing 55 the wear of the disk as above described is preferable.

When initially placing the transfer disks 31 between the worksheet strips 25, it is desirable 60 to have considerable looseness between the strips 25, although, while typing, this looseness, if still present, might cause air pockets to be formed between the worksheet strips and the carbon disks with the result that typing might be blurred. To obtain the advantage and avoid the disadvantage just referred to, the front arm 42 of the carbon arm carrying frame is provided with a 65 pair of spring fingers 52 normally biased to move outwardly away from the web but held inwardly toward the uppermost worksheet 25 by an arm 53 pivoted at 54 and having a flat portion 55 engaging the spring arms 52 where they adjoin. By raising and lowering this arm 53 the operator may provide or remove looseness between the strips 25.

75 As shown in Fig. 17, the paper fingers 57 and

58 and the movable paper fingers 52 are carried by a block 54a having an edge 54b in contact with an edge 42a of the arm 42 of the frame 34 which extends down in front of the worksheets. The block 54a is secured to the arm 42 by a screw 54c passing through an ear 42b on the arm 42 and threaded in the block 54a. The block 54a is slideable vertically relative to the arm 42 for the purpose of raising and lowering the fingers 52 and 57 relative to the line of writing, and to permit this the ear 42b may be provided with a slot 42c in which the screw 54c may ride when the latter is loosened. To adjust the paper guide device, including the block 54a which carries the various parts, the screw 54c is loosened, the block 54a moved up or down as desired, and then the screw 54c is tightened to hold the block 54a in adjusted position.

To avoid the leading edge or other portions of the paper, such as the line of transverse perforations 56, catching onto the arm 42 when the paper is advanced, the end of the arm 42 may be provided with depending paper fingers 57, and these may be formed integral with an upwardly extending finger 58 which tends to hold the worksheet strips from falling forwardly. In fact, the fingers 52 may, as shown, be formed integral with the fingers 57 and 58, but only the fingers 52, in the preferred form of the invention, are made movable toward and from the worksheets.

The carbon disk 31 is mounted on the carbon arm 32 as shown in Figs. 6, 7 and 8. Each carbon disk has a central aperture 59 adapted to fit onto a stud 60 carried near the end of the arm 32. On this stud there is a downwardly projecting finger 61 terminating in a point 62 lying close to the lower edge 63 of a metal disk 64 carried by the end 65 of the carbon arm 32. To apply the carbon disk, it is slightly bent as shown in Fig. 8 so that the end 62 of the finger 61 may pass through the aperture 59. The disk is then drawn upwardly until the aperture clears a slight upwardly extending projection 66 on the finger 61 to the position shown in Fig. 7. If in this position it is allowed to fall by gravity, the 110 disk will be prevented from slipping off the stud or bearing 60 by the projection 66. In actual operation, the thrust of the disk 31 on the stud 60 is upward and thus, with the finger 61 preventing it, there is no danger of the disk falling 115 off the pin forwardly. When out of contact with the paper, however, there is no thrust on the disk except the force of gravity and, should the disk tend to fall forwardly off the stud, this would be prevented by the projection 66.

It should be noted that while there is usually one carbon arm and disk for each carbon copy which is to be made of the work done or the original or uppermost sheet or strip, it is within the purview of this invention to have two arms and 135 two disks for any or all of such copies. This is shown in Fig. 5, in which there are two disks 31 and 31a between the worksheets 25a and 25b. This arrangement may be employed when it is desired to have the impressions on the copies 140 made in different colors at different times. For instance, one carbon disk may give a black impression while the other gives a red. This can be accomplished merely by pressing the control button 41 for the arm carrying the black disk 145 31 to release it and allow the disk to be moved up by the spring 37 and at the same time manually press the arm 32 carrying the red disk 31a down into operative position.

It will thus be seen that by the present inven-

tion a bichrome printing arrangement is effected and further that non-printing may be effected merely by pushing the buttons 41 to allow the carbon disks to be raised out of the line of writing.

In order to adjust the device to the platen of the particular typewriter with which it is used, instead of the eccentric 48 being carried directly on the arm 43, it is mounted on a separate arm 10 67 pivoted on a screw 68 carried by the arm 43 and it is clamped to the arm 43 in adjusted position by a screw 69 in the arm 43 riding in a slot 70 in the lever 67. If the platens of all the machines with which the attachment is to be used 15 were of the same diameter and the lines of writing were at the same distances from the tops of the platen, this adjustment would not be needed.

As above stated, the carbon-arm frame 34 is 20 secured to a shaft having a noncircular extension 45 and this is mounted in a fitting 47 of a supporting structure. This will now be described.

The vertical standard 72 has a vertical extension 71 preferably in the form of a tube cast 25 therein and of noncircular formation, preferably square, which extends into and is clamped within one half 73 of the fitting 47. The portion 73 of the fitting has a vertical slot 74 therein and also has screw-threads 75 by means of which a cap 76 is applied to the part 73 to close the open 30 side of the slot 74, and also to form a bearing for a clamping screw 77, the inner end of which engages the vertical supporting tube 71. By loosening the screw 77, the fitting 47 may be raised 35 and lowered on the supporting frame 72.

The part 73 of the fitting 47 also has a stud 78 which has a bearing in the other half 79 of the fitting, so that the two parts of the fitting may rotate relatively. The end of the stud has 40 a washer 80 secured thereto and between the washer 80 and a flange 81 on the part 79 there is interposed a spring 82 which tends to draw a shouldered portion of the part 73 against the part 79 to yieldingly resist rotation of the halves 73 45 and 79 of the fitting 47, and also to take up any wear which may occur between these parts.

The part 79 of the fitting also has a slot 83 50 therein and the open side of this slot is closed by a cap 84 similar to the cap 76 of the part 73. This slot receives the noncircular extension 45 of the carbon-arm supporting arm and it is held in the part 79 of the fitting by a screw 85.

Thus it will be seen, that the carbon-arm frame 34 may be swung in a vertical plane on the shaft 55 33, and then with its extension 45 may be swung upwardly and backwardly about the center of the fitting 47 to the position shown in dotted lines in Fig. 3, where it will be entirely out of the way, the portions 73 and 79 of the fitting rotating 60 relatively for this purpose.

In order to stop rotation of the carbon-arm frame in the positions shown in full lines and dot-and-dash lines in Fig. 3, the part 73 of the fitting 47 is provided with two pins 86 and 87 65 between which a pin 88 on the part 79 may operate. In the normal position of the carbon-arm frame 34, the pin 88 rests against the pin 86, but, when the carbon frame 34 is moved upwardly and rearwardly and assumes a horizontal position, the pin 88 engages the pin 87.

From the above it will be observed that when 70 the supporting tube 71 is located at a certain place with relation to the typewriter, which place depends somewhat upon the particular structure 75 of the typewriter to which the device is applied,

the carbon-arm frame 34 may be adjusted vertically by loosening the screw 77 and sliding the fitting 47 up and down. It may also be adjusted backwardly and forwardly by loosening the screw 85 and sliding the square tube 45 relative to the fitting 47. Thus, the fitting 47 constitutes a universal union for securing the tubes 45 and 71 together in the desired relationship and, besides this, forms a pivot point about which the carbon-arm frame may be swung. 80 85

The supporting means for attaching the standard 72 and its vertical tube 71 to any of the different makes of front-strike typewriters now on the market is shown in Figs. 1 and 3. The main portion of this clamping bracket comprises a frame 89 extending from front to back and adapted to be located at one side of the typewriter. At the back end, this frame has a hook portion 90 which engages under a lower side rail 91 of the typewriter. At its front end the frame 89 has an arm 92 adapted to hook under and engage the front portion of the rail 91. The arm 92 is adjustable backwardly and forwardly with relation to the frame 89 and is held in adjusted position by a pair of nuts 93, 95 one below the arm 92 and the other above the frame 89, and said nuts being carried by a threaded rod 94 passing through aligned elongated slots in the frame 89 and arm 92. 90 100 105

The threaded rod 94 extends upwardly and at its upper end carries a block 95, see Fig. 18, having an inverted U-shaped horizontal slot in which a U-shaped bar 96 slides. The bar 96 may have any shape desired—the U-shape shown being employed for the purpose of strengthening it. At one end 97 the bar 96 is adapted to rest upon and engage some part 98 of the typewriter frame. In the construction shown, it rests upon the top plate at the forward part of the machine. This top plate is usually provided with a depending flange 99 and the bar 96 has a clamping block 100 slidably mounted in depending arms 101 and having a V-shaped track 102 engaged by V-shaped projections on the block 100. The sliding block 100 has a hook 103 which may be drawn up under the flange 99 by means of a draw screw 104 cast in the clamping block 100 and drawn upwardly by a nut 105 engaging the top surface of the bar 96. 110 115 120 125

In adjusting the supporting device to a typewriter, the arm 92 is so placed on the frame 89 that the hook on the arm and frame may engage the side rail of the typewriter. The threaded rod 94 is then placed in such a position backwardly or forwardly on the frame 89 that its clamping block 100 may engage a suitable portion of the typewriter. The nuts 93 are then tightened to secure the arm 92 and frame 89 together. Then the block 96 is slid toward or from the threaded rod 94 to bring it to desired position, after which the nut 105 is adjusted to draw the hook 103 on the sliding block 100 into proper position. After this is done, a nut 106 carried by the threaded rod 94 and engaging the block 95 (which has a clearance hole 107 through which the rod passes) draws the frame 89 and arm 92 tightly upwardly against the lower rail 91 of the typewriter. 130 135 140

The standard 72 and its tube 71 could be carried directly by the clamping bracket frame 89 for most purposes. However, in order to make the device universal for all kinds of front-strike typewriting machines, further horizontal and vertical adjustments are provided. 145 150

For this purpose the standard 72 is provided with a horizontal portion 108 adjustable relative to an L-shaped bracket 109 in a horizontal plane. These parts are adapted to be secured together in adjusted position by a bolt 110. The L-shaped bracket 109 is mounted in a vertically disposed slot in the frame 89 and is held in vertically adjusted position by a clamp 111 carried by a threaded stud 112 threaded or cast in the bracket 89 and carrying a nut 113 by means of which the clamp may engage and firmly hold the L-shaped bracket to the frame 109, the L-shaped bracket being provided with an elongated slot 114 to permit its vertical movement relative to the stud 112.

The typewriter herein selected for the purpose of illustrating the invention is of the kind wherein the platen moves step-by-step to carry the worksheets across the printing point of the machine. However, it should be understood that the various features of the present invention apply equally well to a kind of machine such as a teletype typewriter, wherein the type basket travels relative to the platen.

Variations and modifications may be made within the scope of this invention and portions of the improvements may be used without others.

Having thus described the invention, what is claimed as new and for which it is desired to obtain Letters-Patent, is:—

1. In a typewriting machine, a platen; type mechanism having a common printing point; a transfer disk; and means mounted at one side only of the machine and above the platen and extending obliquely toward said printing point for supporting said transfer disk between worksheets superposed on the platen for rotation about an axis above said printing point, so that the annular margin of the disk will roll between said worksheets in the line of writing thereof during relative letter-space movement between the platen and the type mechanism as a result of the tractive engagement of the annular margin of the disk with the portions of the worksheets at or adjacent the line of writing.

2. In a manifolding device for a typewriter having a cylindrical platen; means for rotatably supporting disks of transfer material between portions of superposed worksheets which are carried by the platen and located at the line of writing of the typewriter, said disks being rotated as a line is being written; and means for automatically raising and lowering the transfer disks relative to the line of writing as the line is being written.

3. In a manifolding device for a typewriter having a cylindrical platen; means for rotatably supporting disks of transfer material between portions of superposed worksheets which are carried by the platen and located at the line of writing of the typewriter, said disks being rotated as a line is being written; and means for automatically altering the relation of the transfer disks to the line of writing as the typewriting proceeds line by line.

4. In a manifolding device for a typewriter having type mechanism, a platen, and a returnable carriage adapted to travel step-by-step in letter-feed direction; means for rotatably supporting disks of transfer material between portions of superposed worksheets which are carried by the platen and located at the line of writing of the typewriter, said disks being rotated as said carriage travels in letter-feed di-

rection—by frictional contact between the disks and the worksheets—as a line is being written; and means operated as an incident to the return of the carriage to begin a new line of writing to cause a portion of the transfer disk to be located at the printing point different from that so located at the beginning of the last line of writing.

5. In a manifolding device for a typewriter having type mechanism, a platen, and a returnable carriage adapted to travel step-by-step in letter-feed direction; means for rotatably supporting disks of transfer material between portions of superposed worksheets which are carried by the platen and located at the line of writing of the typewriter, said disks being rotated as said carriage travels in letter-feed direction—by frictional contact between the disks and the worksheets—as a line is being written; and means operated as a result of the letter-feed movements of the carriage as a line is being written for automatically raising and lowering the transfer disks relative to the line of writing as a line is being written.

6. In a manifolding device for a typewriter having type mechanism, a platen, and a returnable carriage adapted to travel step-by-step in letter-feed direction; means for rotatably supporting disks of transfer material between portions of superposed worksheets which are carried by the platen and located at the line of writing of the typewriter, said disks being rotated as said carriage travels in letter-feed direction—by frictional contact between the disks and the worksheets—as a line is being written; means operated as a result of the letter-feed movements of the carriage as a line is being written for automatically raising and lowering the transfer disks relative to the line of writing as a line is being written; and means for holding the transfer disks in the positions they assume vertically with relation thereto at the end of a line of writing during the return movements of the carriage.

7. In a manifolding device for a typewriter having type mechanism, a platen, and a returnable carriage adapted to travel step-by-step in letter-feed direction; means for rotatably supporting disks of transfer material between portions of superposed worksheets which are carried by the platen and located at the line of writing of the typewriter, said disks being rotated as said carriage travels in letter-feed direction as a line is being written; and means operated as an incident to the return of the carriage to begin a new line of writing to cause a portion of the transfer disk to be located at the printing point different from that so located at the beginning of the last line of writing.

8. In a manifolding device for a typewriter having type mechanism, a platen, and a returnable carriage adapted to travel step-by-step in letter-feed direction; means for rotatably supporting disks of transfer material between portions of superposed worksheets which are carried by the platen and located at the line of writing of the typewriter, said disks being rotated as said carriage travels in letter-feed and return direction as a line is being written; and means operated as an incident to the return of the carriage to begin a new line of writing to cause a portion of the transfer disk to be located at the printing point different from that so located at the beginning of the last line of writing.

9. In a manifolding device for a typewriter having a cylindrical platen; means for rotatably

- supporting a disk of transfer material between portions of superposed worksheets which are carried by the platen and located at the line of writing of the typewriter, said disk being rotated as a line is being written; and means for causing the transfer material of the disk to be consumed along undulating lines extending over a wide angular margin of the disk and starting at an infinite number of points angularly around the disk.
10. In a manifolding device for a typewriter having a cylindrical platen; arms extending from the side of the typewriter toward the printing point and adapted to carry transfer disks in the line of writing of the platen and at the printing point; means normally tending to lift each arm and move the transfer disks carried thereby from the line of writing to a position directly above and spaced slightly from the line of writing; and manually controlled means restraining said arms against movement under the influence of the last-named means.
11. In a manifolding device for a typewriter having a cylindrical platen; arms extending from the side of the typewriter toward the printing point and adapted to carry transfer disks in the line of writing of the platen and at the printing point; springs normally tending to lift each arm and the transfer disks carried thereby from operative position in the line of writing to inoperative position directly above and spaced slightly from the line of writing; and manually releasable catches for holding the arms in operative position.
12. In a manifolding device for a typewriter having a cylindrical platen; arms extending from the side of the typewriter toward the printing point and adapted to carry transfer disks in the line of writing of the platen and at the printing point; a frame supporting said carbon-carrying arms for movement en bloc upwardly and entirely away from the platen; and a support for carrying said frame downwardly and backwardly so that the carbon-carrying arms extend from front to back at the side of the typewriter.
13. In a manifolding device for a typewriter having a cylindrical platen; arms extending from the side of the typewriter toward the printing point and adapted to carry transfer disks in the line of writing of the platen and at the printing point; a frame supporting said carbon-carrying arms for movement en bloc upwardly and entirely away from the platen; a support for carrying said frame downwardly and backwardly so that the carbon-carrying arms extend from front to back at the side of the typewriter; and a bracket for securing said support to the typewriter.
14. In a manifolding device for a typewriter having a cylindrical platen; arms extending from the side of the typewriter toward the printing point and adapted to carry transfer disks in the line of writing of the platen and at the printing point; a frame supporting said carbon-carrying arms for movement en bloc upwardly and entirely away from the platen; a support for carrying said frame downwardly and backwardly so that the carbon-carrying arms extend from front to back at the side of the typewriter; a bracket secured to the typewriter; and means adjustably connecting the bracket to said supporting means for adjustment in both vertical and horizontal planes.
15. In a manifolding device for a typewriter having a cylindrical platen; arms extending from the side of the typewriter toward the printing point and adapted to carry transfer disks in the line of writing of the platen and at the printing point; a frame supporting said carbon-carrying arms for movement en bloc upwardly and entirely away from the platen; a support carrying said frame and including a swivel joint about which the frame may be swung downwardly and rearwardly; and a standard carrying said swivel joint for adjustment vertically.
16. In a manifolding device for a typewriter having a cylindrical platen; arms extending from the side of the typewriter toward the printing point and adapted to carry transfer disks in the line of writing of the platen and at the printing point; a frame supporting said carbon-carrying arms for movement en bloc upwardly and entirely away from the platen; a support carrying said frame and including a swivel joint about which the frame may be swung downwardly and rearwardly; and a standard carrying said swivel joint for adjustment vertically, said frame being adjustable horizontally in the swivel joint to bring the carbon disks carried by said arms to the line of writing of the typewriter.
17. In a manifolding device for a typewriter having a cylindrical platen; arms extending from the side of the typewriter toward the printing point and adapted to carry transfer disks in the line of writing of the platen and at the printing point; a frame for supporting said arms extending substantially parallel with the arms toward the line of writing; and paper fingers carried by the end of the frame and located in the plane of and to the side of the printing point of the machine.
18. In a manifolding device for a typewriter having a cylindrical platen; and means for rotatably and independently supporting a plurality of disks of transfer material of different colors between adjacent superposed worksheets, said means being mounted for movement from an inoperative position adjacent the line of writing to an operative position in the line of writing so that the disk of either color may be optionally brought into the line of writing.
19. In a manifolding device for a typewriter having a cylindrical platen; means for rotatably supporting a disk of transfer material between portions of superposed worksheets which are carried by the platen and located at the line of writing of the typewriter, said disk being rotated as a line is being written; and a member in slidable engagement with the surface of the platen and connected to said transfer disk-supporting means for supporting the latter with the margin of the transfer disk in the line of writing.
20. In a manifolding device for a typewriter having a cylindrical platen; means for rotatably supporting a disk of transfer material between portions of superposed worksheets which are carried by the platen and located at the line of writing of the typewriter, said disk being rotated as a line is being written; and a member in slidable engagement with the surface of the platen and connected to said transfer disk-supporting means for determining the distance between the axis of the transfer disk and the line of writing.
21. In a manifolding device for a typewriter having a cylindrical platen; means for rotatably supporting a disk of transfer material between portions of superposed worksheets which are carried by the platen and located at the line of writing of the typewriter, said disk being rotated as a line is being written; a member in slidable engagement with the surface of the platen; and an

- letter-space movements between the platen and the type mechanism; means for connecting said roller to the transfer disk-supporting means so that the latter is supported in operative position
- 5 by the roller and platen, said roller being eccentrically mounted on said connecting means to cause the transfer disk to be automatically raised and lowered relative to the line of writing as a result of the rotation of the roller caused by relative movement between the roller and the platen as a line is being written; means for adjusting the connection between the roller and the transfer disk-supporting means for determining the distance between the axis of the transfer disk and the line of writing for any given point in the position of the eccentrically mounted roller; and means for preventing rotation of said roller during returning relative movement between the platen and type mechanism to cause a portion of
- 10 the transfer disk to be located at the printing point different from that so located at the beginning of the last line of writing.
- 15 31. In a manifolding device for a typewriter having a cylindrical platen; means for rotatably supporting a disk of transfer material between portions of superposed worksheets which are carried by the platen and located at the line of writing of the typewriter, said disk being rotated as a line is being written; and a member connected to the transfer disk-supporting means rotated as a line is being written upon and held against rotation while preparing to write a new line for causing the transfer material of the disk to be consumed along undulating lines extending over a wide annular margin of the disk and starting at an infinite number of points angularly around the disk.
- 20 32. A manifolding device for a typewriter having type mechanism, a platen, and a returnable carriage adapted to travel step-by-step in letter-feed direction; a plurality of means each for rotatably supporting a disk of transfer material between portions of superposed worksheets which are carried by the platen and located at the line of writing of the typewriter, said disks being rotated as the carriage travels in letter-feed direction during the writing of a line; a frame supporting said plurality of transfer disk-carrying means on which frame each of the last-named
- 25 means is pivotally mounted; means for holding said transfer disk-carrying means in operative position on said frame; and a member in slid-able engagement with the surface of the platen and connected to said frame for holding the latter in operative position so that the margin of each transfer disk is located in the line of writing.
- 30 33. A manifolding device for a typewriter having type mechanism, a platen, and a returnable carriage adapted to travel step-by-step in letter-feed direction; a plurality of means each for rotatably supporting a disk of transfer material between portions of superposed worksheets which are carried by the platen and located at the line of writing of the typewriter, said
- 35 disks being rotated as the carriage travels in letter-feed direction during the writing of a line; a frame supporting said plurality of transfer disk-carrying means on which frame each of the last-named means is pivotally mounted; means for holding said transfer disk-carrying means in operative position on said frame; and an eccentrically mounted roller riding on the upper surface of the platen and connected to said frame for automatically raising and lowering all the transfer disks as a group relative to the line of writing upon relative movement between the platen and the roller as the line is being written.
- 40 34. A manifolding device for a typewriter having type mechanism, a platen, and a returnable carriage adapted to travel step-by-step in letter-feed direction; a plurality of means each for rotatably supporting a disk of transfer material between portions of superposed worksheets which are carried by the platen and located at the line of writing of the typewriter, said disks being rotated as the carriage travels in letter-feed direction during the writing of a line; a frame supporting said plurality of transfer disk-carrying means on which frame each of the last-named means is pivotally mounted; means for holding said transfer disk-carrying means in operative position on said frame; a member in slid-able engagement with the surface of the platen; and an adjustable connection between said member and said frame for variably determining the distance between the axes of all the transfer disks when the latter are in operative position and the line of writing.
- 45 35. A manifolding device for a typewriter having type mechanism, a platen, and a returnable carriage adapted to travel step-by-step in letter-feed direction; a plurality of means each for rotatably supporting a disk of transfer material between portions of superposed worksheets which are carried by the platen and located at the line of writing of the typewriter, said disks being rotated as the carriage travels in letter-feed direction during the writing of a line; a frame supporting said plurality of transfer disk-carrying means on which frame each of the last-named
- 50 means is pivotally mounted; means for holding said transfer disk-carrying means in operative position on said frame; and a roller riding on the upper surface of the platen and connected to said frame for determining the distance between the axes of all the transfer disks when the latter are in operative position and the line of writing.
- 55 36. A manifolding device for a typewriter having type mechanism, a platen, and a returnable carriage adapted to travel step-by-step in letter-feed direction; a plurality of means each for rotatably supporting a disk of transfer material between portions of superposed worksheets which are carried by the platen and located at the line of writing of the typewriter, said disks being rotated as the carriage travels in letter-feed direction during the writing of a line; a frame supporting said plurality of transfer disk-carrying means on which frame each of the last-named means is pivotally mounted; means for holding said transfer disk-carrying means in operative position on said frame; and a member in slid-able engagement with the surface of the platen and connected to said frame for holding the latter in operative position so that the margin of each transfer disk is located in the line of writing.
- 60 37. A manifolding device for a typewriter having type mechanism, a platen, and a returnable carriage adapted to travel step-by-step in letter-feed direction; a plurality of means each for rotatably supporting a disk of transfer material between portions of superposed worksheets which are carried by the platen and located at the line of writing of the typewriter, said disks being rotated as the carriage travels in letter-feed direction during the writing of a line; a frame supporting said plurality of transfer disk-carrying means on which frame each of the last-named means is pivotally mounted; means for holding said transfer disk-carrying means in operative position on said frame; and a member in slid-able engagement with the surface of the platen and connected to said frame for determining the distance between the axes of all the transfer disks when the latter are in operative position and the line of writing.
- 65 38. A manifolding device for a typewriter having type mechanism, a platen, and a returnable carriage adapted to travel step-by-step in letter-feed direction; a plurality of means each for rotatably supporting a disk of transfer material between portions of superposed worksheets which are carried by the platen and located at the line of writing of the typewriter, said disks being rotated as the carriage travels in letter-feed direction during the writing of a line; a frame supporting said plurality of transfer disk-carrying means on which frame each of the last-named means is pivotally mounted; means for holding said transfer disk-carrying means in operative position on said frame; and a member in slid-able engagement with the surface of the platen and connected to said frame for determining the distance between the axes of all the transfer disks when the latter are in operative position and the line of writing.
- 70 39. A manifolding device for a typewriter having type mechanism, a platen, and a returnable carriage adapted to travel step-by-step in letter-feed direction; a plurality of means each for rotatably supporting a disk of transfer material between portions of superposed worksheets which are carried by the platen and located at the line of writing of the typewriter, said disks being rotated as the carriage travels in letter-feed direction during the writing of a line; a frame supporting said plurality of transfer disk-carrying means on which frame each of the last-named means is pivotally mounted; means for holding said transfer disk-carrying means in operative position on said frame; and a member in slid-able engagement with the surface of the platen and connected to said frame for determining the distance between the axes of all the transfer disks when the latter are in operative position and the line of writing.
- 75 40. A manifolding device for a typewriter having type mechanism, a platen, and a returnable carriage adapted to travel step-by-step in letter-feed direction; a plurality of means each for rotatably supporting a disk of transfer material between portions of superposed worksheets which are carried by the platen and located at the line of writing of the typewriter, said disks being rotated as the carriage travels in letter-feed direction during the writing of a line; a frame supporting said plurality of transfer disk-carrying means on which frame each of the last-named means is pivotally mounted; means for holding said transfer disk-carrying means in operative position on said frame; and a member in slid-able engagement with the surface of the platen and connected to said frame for determining the distance between the axes of all the transfer disks when the latter are in operative position and the line of writing.

- means on which frame each of the last-named means is pivotally mounted; means for holding said transfer disk-carrying means in operative position on said frame; a roller riding on the upper surface of the platen and rotated by the letter-space movements between the platen and the type mechanism; and means for connecting said roller to said frame so that the group of transfer disk-supporting means is supported in operative position by the roller and platen. 10
38. A manifolding device for a typewriter having type mechanism, a platen, and a returnable carriage adapted to travel step-by-step in letter-feed direction; a plurality of means each for rotatably supporting a disk of transfer material between portions of superposed worksheets which are carried by the platen and located at the line of writing of the typewriter, said disks being rotated as the carriage travels in letter-feed direction during the writing of a line; a frame supporting said plurality of transfer disk-carrying means on which frame each of the last-named means is pivotally mounted; means for holding said transfer disk-carrying means in operative position on said frame; a roller riding on the upper surface of the platen and rotated by the letter-space movements between the platen and the type mechanism; and means for connecting said roller to said frame so that the group of transfer disk-supporting means is supported in operative position by the roller and platen, said roller being eccentrically mounted on said connecting means to cause the transfer disks as a group to be automatically raised and lowered relative to the line of writing as a result of the rotation of the roller caused by the relative movement between the roller and the platen as a line is being written. 30
39. A manifolding device for a typewriter having type mechanism, a platen, and a returnable carriage adapted to travel step-by-step in letter-feed direction; a plurality of means each for rotatably supporting a disk of transfer material between portions of superposed worksheets which are carried by the platen and located at the line of writing of the typewriter, said disks being rotated as the carriage travels in letter-feed direction during the writing of a line; a frame supporting said plurality of transfer disk-carrying means on which frame each of the last-named means is pivotally mounted; means for holding said transfer disk-carrying means in operative position on said frame; a roller riding on the upper surface of the platen and rotated by the letter-space movements between the platen and the type mechanism; and an adjustable connection between the roller and said frame for determining the distance between the axes of all the transfer disks when in operative position and the line of writing. 50
40. A manifolding device for a typewriter having type mechanism and a platen; a plurality of means each for rotatably supporting a disk of transfer material between portions of superposed worksheets which are carried by the platen and located at the line of writing of the typewriter, said disk being rotated upon relative letter-feed movement between the platen and the type mechanism as a line is being written; a frame for supporting said transfer disk-supporting means as a group, said frame extending to the vicinity of the printing point of the machine; and a paper guide carried by said frame at the printing point, said paper guide having a pair of arms extending downwardly across the line of writing, one arm being located at each side of the printing point, said paper guide having a pair of arms extending downwardly across the line of writing, 60
- one arm being located at each side of the printing point. 5
41. A manifolding device for a typewriter having type mechanism and a platen; a plurality of means each for rotatably supporting a disk of transfer material between portions of superposed worksheets which are carried by the platen and located at the line of writing of the typewriter, said disk being rotated upon relative letter-feed movement between the platen and the type mechanism as a line is being written; a frame for supporting said transfer disk-supporting means as a group, said frame extending to the vicinity of the printing point of the machine; and a paper guide carried by said frame at the printing point, said paper guide having a pair of arms extending downwardly across the line of writing, one arm being located at each side of the printing point, said arms at their lower ends flaring downwardly and forwardly. 80
42. A manifolding device for a typewriter having type mechanism and a platen; a plurality of means each for rotatably supporting a disk of transfer material between portions of superposed worksheets which are carried by the platen and located at the line of writing of the typewriter, said disk being rotated upon relative letter-feed movement between the platen and the type mechanism as a line is being written; a frame for supporting said transfer disk-supporting means as a group, said frame extending to the vicinity of the printing point of the machine; and a paper guide carried by said frame at the printing point, said paper guide having an arm extending upwardly beyond the line of writing to support the leading ends of the worksheets against falling over forwardly. 90
43. A manifolding device for a typewriter having type mechanism and a platen; a plurality of means each for rotatably supporting a disk of transfer material between portions of superposed worksheets which are carried by the platen and located at the line of writing of the typewriter, said disk being rotated upon relative letter-feed movement between the platen and the type mechanism as a line is being written; a frame for supporting said transfer disk-supporting means as a group, said frame extending to the vicinity of the printing point of the machine; and a paper guide carried by said frame at the printing point, said paper guide having a pair of arms extending downwardly across the line of writing, one arm being located at each side of the printing point, and an arm extending upwardly beyond the line of writing to support the leading ends of the worksheets against falling over forwardly. 100
44. A manifolding device for a typewriter having type mechanism and a platen; a plurality of means each for rotatably supporting a disk of transfer material between portions of superposed worksheets which are carried by the platen and located at the line of writing of the typewriter, said disk being rotated upon relative letter-feed movement between the platen and the type mechanism as a line is being written; a frame for supporting said transfer disk-supporting means as a group, said frame extending to the vicinity of the printing point of the machine; and a paper guide carried by said frame at the printing point, said paper guide having a finger extending toward the line of writing and movable toward and from the worksheets carried by the platen, and a finger-piece for moving said finger toward and from the work- 110

- sheets to urge the latter toward the platen at the printing point.
45. A manifolding device for a typewriter having type mechanism and a platen; a plurality of means each for rotatably supporting a disk of transfer material between portions of superposed worksheets which are carried by the platen and located at the line of writing of the typewriter, said disk being rotated upon relative letter-feed movement between the platen and the type mechanism as a line is being written; a frame for supporting said transfer disk-supporting means as a group, said frame extending to the vicinity of the printing point of the machine; and a paper guide carried by said frame at the printing point, said paper guide having a pair of arms extending downwardly across the line of writing, one arm being located at each side of the printing point, a finger extending toward the line of writing and movable toward and from the worksheets carried by the platen, and a finger-piece for moving said finger toward and from the worksheets to urge the latter toward the platen at the printing point.
46. A manifolding device for a typewriter having type mechanism and a platen; a plurality of means each for rotatably supporting a disk of transfer material between portions of superposed worksheets which are carried by the platen and located at the line of writing of the typewriter, said disk being rotated upon relative letter-feed movement between the platen and the type mechanism as a line is being written; a frame for supporting said transfer disk-supporting means as a group, said frame extending to the vicinity of the printing point of the machine; and a paper guide carried by said frame at the printing point, said paper guide having an arm extending upwardly beyond the line of writing to support the leading ends of the worksheets against falling over forwardly, a finger extending toward the line of writing and movable toward and from the worksheets carried by the platen, and a finger-piece for moving said finger toward and from the worksheets to urge the latter toward the platen at the printing point.
47. A manifolding device for a typewriter having type mechanism and a platen; a plurality of means each for rotatably supporting a disk of transfer material between portions of superposed worksheets which are carried by the platen and located at the line of writing of the typewriter, said disk being rotated upon relative letter-feed movement between the platen and the type mechanism as a line is being written; a frame for supporting said transfer disk-supporting means as a group, said frame extending to the vicinity of the printing point of the machine; and a paper guide carried by said frame at the printing point, said paper guide having a pair of arms extending downwardly across the line of writing, one arm being located at each side of the printing point, an arm extending upwardly beyond the line of writing to support the leading ends of the worksheets against falling over forwardly, a finger extending toward the line of writing and movable toward and from the worksheets carried by the platen, and a finger-piece for moving said finger toward and from the worksheets to urge the latter toward the platen at the line of writing.
48. A manifolding device for a typewriter having type mechanism and a platen; a plurality of means each for rotatably supporting a disk of transfer material between portions of superposed worksheets which are carried by the platen and located at the line of writing of the typewriter, said disk being rotated upon relative letter-feed movement between the platen and the type mechanism as a line is being written; a frame for supporting said transfer disk-supporting means as a group, said frame extending to the vicinity of the printing point of the machine; and a paper guide carried by said frame at the printing point, said paper guide being slidably mounted on said frame for vertical movement relative to the frame toward and from the line of writing, and means for securing the paper guide in adjusted position.
49. A manifolding device for a typewriter having type mechanism, a platen, and a returnable carriage adapted to travel step-by-step in letter-feed direction; a plurality of means each for rotatably supporting a disk of transfer material between portions of superposed worksheets which are carried by the platen and located at the line of writing of the typewriter, said disks being rotated as the carriage travels in letter-feed direction during the writing of a line; a frame supporting said plurality of transfer disk-carrying means on which frame each of the last-named means is pivotally mounted; means for holding said transfer disk-carrying means in operative position on said frame; a member in slidable engagement with the surface of the platen; an adjustable connection between said member and said frame for variably determining the distance between the axes of all the transfer disks when the latter are in operative position and the line of writing, said frame having a portion extending to the vicinity of the printing point of the machine and in front of the worksheets carried by the platen; a paper guide carried by the last-named portion of the frame at the printing point, said paper guide being slidably mounted on said portion of the frame for vertical movement relative to the frame toward and from the line of writing; and means for securing said paper guide in adjusted position.
50. A manifolding device for a typewriter having type mechanism, a platen, and a returnable carriage adapted to travel step-by-step in letter-feed direction; a plurality of means each for rotatably supporting a disk of transfer material between portions of superposed worksheets which are carried by the platen and located at the line of writing of the typewriter, said disks being rotated as the carriage travels in letter-feed direction during the writing of a line; a frame supporting said plurality of transfer disk-carrying means on which frame each of the last-named means is pivotally mounted; means for holding said transfer disk-carrying means in operative position on said frame; a member in slidable engagement with the surface of the platen; an adjustable connection between said member and said frame for variably determining the distance between the axes of all the transfer disks when the latter are in operative position and the line of writing, said frame having a portion extending to the vicinity of the printing point of the machine and in front of the worksheets carried by the platen; a paper guide carried by the last-named portion of the frame at the printing point, said paper guide being slidably mounted on said portion of the frame for vertical movement relative to the frame toward and from the line of writing; and means for securing said paper guide in adjusted position.

- movable toward and from the worksheets carried by the platen, and a finger-piece for moving said finger toward and from the worksheets to urge the latter toward the platen at the printing point.
51. In a manifolding device for a typewriter having a cylindrical platen; means for rotatably supporting a disk of transfer material between portions of superposed worksheets which are carried by the platen and located at the line of writing of the typewriter, said disk being rotated as a line is being written; and means normally tending to lift the transfer disk-carrying means to move the transfer disk carried thereby from an operative position in the line of writing to an inoperative position where the transfer disk is still interposed between the worksheets but is located above the line of writing. 80
52. In a manifolding device for a typewriter having a cylindrical platen; arms extending from the side of the typewriter toward the printing point and adapted to carry transfer disks in the line of writing of the platen and at the printing point; springs normally tending to lift each arm and move the transfer disks carried thereby from an operative position in the line of writing to an inoperative position directly above and spaced slightly from the line of writing; a plurality of catches, one for each arm, for holding said arms in operative position; and a finger-piece on each catch whereby a catch may be operated to release its associated arm for movement out of a line of writing to said inoperative position. 85
53. In a manifolding device for a typewriter having a cylindrical platen; arms extending from the side of the typewriter toward the printing point and adapted to carry transfer disks in the line of writing of the platen and at the printing point; springs normally tending to lift each arm and move the transfer disks carried thereby from an operative position in the line of writing to an inoperative position directly above and spaced slightly from the line of writing; a plurality of catches, one for each arm, for holding said arms in operative position; and a finger-piece on each catch whereby a catch may be operated to release its associated arm for movement out of a line of writing to said inoperative position, said finger-pieces being arranged in a row and projecting 90
54. In a typewriting machine, a platen; type mechanism; a transfer disk; a bar carrying said transfer disk, the transfer disk having a bearing aperture; a stud on the bar for receiving said bearing aperture and rotatably supporting the transfer disk; and a finger fixedly carried by said stud and extending radially of the disk when the disk is mounted on the stud for holding the transfer disk on the stud. 95
55. In a typewriting machine, a platen; type mechanism; a transfer disk; a bar carrying said transfer disk, the transfer disk having a bearing aperture; a stud on the bar for receiving said bearing aperture and rotatably supporting the transfer disk; and a finger fixedly carried by said stud and extending radially of the disk when the disk is mounted on the stud for holding the transfer disk on the stud, the portion of the finger attached to the stud projecting beyond the stud in all directions, the bearing aperture in the transfer disk being larger than the stud so as to fit over the said portion of the finger which projects beyond the stud. 100
56. In a typewriting machine, a platen; type mechanism; a transfer disk; a bar carrying said transfer disk, the transfer disk having a bearing aperture; a stud on the bar for receiving said bearing aperture and rotatably supporting the transfer disk; and a finger fixedly carried by said stud and extending radially of the disk when the disk is mounted on the stud for holding the transfer disk on the stud, the portion of the finger attached to the stud projecting beyond the stud in all directions, the bearing aperture in the transfer disk being larger than the stud so as to fit over the said portion of the finger which projects beyond the stud, the finger on the stud projecting downwardly and the disk when loosely supported on the stud having the upper portion of its bearing aperture resting on the stud and held thereon by the said portion of the finger which projects beyond the stud. 105

LOUIS C. ANTRIM.

50 CERTIFICATE OF CORRECTION. 75

Patent No. 1,964,022.

June 26, 1934.

55 LOUIS C. ANTRIM. 80

60 It is hereby certified that error appears in the printed specification of the above numbered patent requiring correction as follows: Page 6, line 29, claim 11, after "and" insert move; and that the said Letters Patent should be read with this correction therein that the same may conform to the record of the case in the Patent Office. 135

65 Signed and sealed this 11th day of September, A. D. 1934. 140

- movable toward and from the worksheets carried by the platen, and a finger-piece for moving said finger toward and from the worksheets to urge the latter toward the platen at the printing point.
51. In a manifolding device for a typewriter having a cylindrical platen; means for rotatably supporting a disk of transfer material between portions of superposed worksheets which are carried by the platen and located at the line of writing of the typewriter, said disk being rotated as a line is being written; and means normally tending to lift the transfer disk-carrying means to move the transfer disk carried thereby from an operative position in the line of writing to an inoperative position where the transfer disk is still interposed between the worksheets but is located above the line of writing. 80
52. In a manifolding device for a typewriter having a cylindrical platen; arms extending from the side of the typewriter toward the printing point and adapted to carry transfer disks in the line of writing of the platen and at the printing point; springs normally tending to lift each arm and move the transfer disks carried thereby from an operative position in the line of writing to an inoperative position directly above and spaced slightly from the line of writing; a plurality of catches, one for each arm, for holding said arms in operative position; and a finger-piece on each catch whereby a catch may be operated to release its associated arm for movement out of a line of writing to said inoperative position. 85
53. In a manifolding device for a typewriter having a cylindrical platen; arms extending from the side of the typewriter toward the printing point and adapted to carry transfer disks in the line of writing of the platen and at the printing point; springs normally tending to lift each arm and move the transfer disks carried thereby from an operative position in the line of writing to an inoperative position directly above and spaced slightly from the line of writing; a plurality of catches, one for each arm, for holding said arms in operative position; and a finger-piece on each catch whereby a catch may be operated to release its associated arm for movement out of a line of writing to said inoperative position, said finger-pieces being arranged in a row and projecting 90
54. In a typewriting machine, a platen; type mechanism; a transfer disk; a bar carrying said transfer disk, the transfer disk having a bearing aperture; a stud on the bar for receiving said bearing aperture and rotatably supporting the transfer disk; and a finger fixedly carried by said stud and extending radially of the disk when the disk is mounted on the stud for holding the transfer disk on the stud. 95
55. In a typewriting machine, a platen; type mechanism; a transfer disk; a bar carrying said transfer disk, the transfer disk having a bearing aperture; a stud on the bar for receiving said bearing aperture and rotatably supporting the transfer disk; and a finger fixedly carried by said stud and extending radially of the disk when the disk is mounted on the stud for holding the transfer disk on the stud, the portion of the finger attached to the stud projecting beyond the stud in all directions, the bearing aperture in the transfer disk being larger than the stud so as to fit over the said portion of the finger which projects beyond the stud. 100
56. In a typewriting machine, a platen; type mechanism; a transfer disk; a bar carrying said transfer disk, the transfer disk having a bearing aperture; a stud on the bar for receiving said bearing aperture and rotatably supporting the transfer disk; and a finger fixedly carried by said stud and extending radially of the disk when the disk is mounted on the stud for holding the transfer disk on the stud, the portion of the finger attached to the stud projecting beyond the stud in all directions, the bearing aperture in the transfer disk being larger than the stud so as to fit over the said portion of the finger which projects beyond the stud, the finger on the stud projecting downwardly and the disk when loosely supported on the stud having the upper portion of its bearing aperture resting on the stud and held thereon by the said portion of the finger which projects beyond the stud. 105

LOUIS C. ANTRIM.

50 CERTIFICATE OF CORRECTION. 75

Patent No. 1,964,022.

June 26, 1934.

55 LOUIS C. ANTRIM. 80

It is hereby certified that error appears in the printed specification of the above numbered patent requiring correction as follows: Page 6, line 29, claim 11, after "and" insert move; and that the said Letters Patent should be read with this correction therein that the same may conform to the record of the case in the Patent Office. 135

65 Signed and sealed this 11th day of September, A. D. 1934. 140

Leslie Frazer

70 (Seal) 85 Acting Commissioner of Patents. 150
